(57) **CLAIM**

We claim an ornamental design for a cookie cutter, as shown and described.

DESCRIPTION

FIG. 1 is a top, front, left perspective view showing our new design for a cookie cutter;

FIG. 2 is a bottom, front, right perspective view thereof;

FIG. 3 is a bottom, rear perspective view thereof;

FIG. 4 a top plan view thereof;

FIG. 5 is a bottom plan view thereof; and,

FIG. 6 is a right side elevational thereof, all other elevational views being mirror images of the right side elevational view.
